(57) **CLAIM**

The ornamental design for a display screen or portion thereof with sudoku icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with sudoku icon;

FIG. 2 is an enlarged view of a portion of FIG. 1;

FIG. 3 is a front view of a second embodiment of the display screen or portion thereof with sudoku icon; and,

FIG. 4 is an enlarged view of a portion of FIG. 3.

The broken lines showing a display screen or portion thereof forms no part of the claimed design. The remaining broken lines showing portions of the icon form no part of the claimed design.

**1 Claim, 1 Drawing Sheet
(1 of 1 Drawing Sheet(s) Filed in Color)**
